PHILIP S. CLAUS, OF DETROIT, MICHIGAN

ENGINE STARTING DEVICE

Application filed April 30, 1932. Serial No. 608,505.

My invention relates to power drives and consists, more particularly, in an improved automatic starter drive for cranking internal combustion engines.

5 The most common and satisfactory starter drive for internal combustion engines now on the market consists essentially of a worm or threaded member rotatively driven by the starter motor, a pinion gear threadedly associated with said worm and projectable thereon, by means of its inertia, into engagement with the engine gear, and a stop element at the end of the worm against which the pinion abuts when projected, and by which 15 the pinion is rotatively locked upon the worm member. In this construction the pinion is projected with respect to the worm and its projective movement is suddenly brought to an instantaneous and complete stop, simultaneously positively locking it upon the worm to pick up the entire load of cranking the engine. Because of the terrific shock inherently incident to the instantaneous stopping of the pinion and picking up of the load, some sort of shock absorbing or cushioning 20 means is an absolutely essential element in a satisfactory device embodying this construction. The conventional cushioning means employed consists of an expanded spiral spring through which the drive is yieldingly transmitted, and by which a certain amount of longitudinal movement of the worm is permitted. The incorporation of the spring does not preclude or eliminate the shock—it serves 25 merely to mitigate an objectionable characteristic inherent in this type of device.

With this and other undesirable features of the prior art devices in mind, my invention has certain well defined objects. A 30 primary object of my invention is to provide a springless automatic starter drive for internal combustion engines and the like, by which the load is gradually and progressively picked up without shock.

Another object of my invention is to provide a starter drive which is substantially noiseless in its engagement with and disengagement from the engine gear.

50 Another object of my invention is to provide a starter drive in which the pinion is

accurately centered upon its shaft to the elimination of the noise, wear, and loss of power incident to misalignment of pinion gear and engine gear.

Another object of my invention is to provide a starter drive in which facile meshing of the pinion and engine gear is assured and burring of the teeth thereof is precluded.

Another object of my invention is to provide a starter drive which releases with ease, 60 and which is not subject to the sticking so common with prior starter drives of the type described.

Another object of my invention is to provide a starter drive in which the pinion gear 65 automatically overruns the starter motor shaft in the event that the engine kicks or runs backward, thus precluding excessive discharge of the battery, breakage or bending of the drive shaft, stripping of gear 70 teeth, or other injury.

Another object of my invention is to provide a shockless starter drive which imparts a rotation to the engine crank shaft which is a true function of the rotation of the starter 75 motor, that is, a cranking movement without the usual period of deceleration due to momentary windup of the drive-cushioning spring each time an engine cylinder is undergoing the compression cycle. Such a cranking movement, free from such periods of deceleration, closely approximates the snappy action characteristic of effective hand cranking as practiced by skillful motorists in the days before the electric starter.

85 Another object of my invention is to provide a starter drive which is simple, which is not subject to wear or breakage, which may be cheaply manufactured by production methods of automatic stamping and machining, and which may be assembled by unskilled workers in a fraction of the time now required to assemble prior art starting drives of the conventional type described.

90 Further objects, and objects relating to details and economies of construction will definitely appear from the detailed description to follow. In one instance I accomplish the objects of my invention by the devices and means set forth in the following speci- 100

ification. My invention is clearly defined in the appended claims. Structures constituting preferred embodiments of my invention are illustrated in the accompanying drawings forming a part of this specification, in which:

Figure 1 is a view in side elevation, of a preferred form of starter drive embodying my invention, fragments only of the starting 10 motor and engine ring gear being shown to illustrate the relationship of the parts when not in operation;

Fig. 2 is a vertical sectional view of the same starter drive;

15 Fig. 3 is a transverse sectional view taken on the line 3—3 of Fig. 2;

Fig. 4 is a transverse sectional view taken on the line 4—4 of Fig. 2;

20 Fig. 5 is a perspective view of the locking clutch member;

Fig. 6 is a view in side elevation, of a modified form of starter drive embodying my invention, fragments only of the starting motor and engine ring gear being shown to 25 illustrate the relationship of the parts when not in operation;

Fig. 7 is a vertical sectional view of the starter drive shown in Fig. 6;

30 Fig. 8 is a transverse sectional view taken on the line 8—8 of Fig. 7;

Fig. 9 is a transverse sectional view taken on the line 9—9 of Fig. 7;

35 Fig. 10 is a detail view of a portion of one of the clutch members, showing the space-providing lug; and

Fig. 11 is a detail view of a portion of the other clutch member constituting a part of the device shown in Fig. 7, showing the lug-receiving notch.

40 Like reference numerals refer to similar parts throughout the several views.

In its broad sense, my invention comprises an engine starter drive including a starting motor driving a shaft upon which are mounted 45 a pair of differentially threaded screw members or worms, the threads of which turn in the same direction but are of different lead or pitch. Carried by the threaded member of lesser pitch is a pinion, preferably a small 50 gear having teeth of the same pitch as the teeth of a large ring gear on the flywheel of the engine. This pinion has a thread or threads which are associated with the threads of the threaded member of lesser pitch and 55 which cause the pinion to move longitudinally into mesh with the ring gear when the threaded member is revolved by the starting motor, and the pinion, by reason of its inertia, is overrun. Carried by the threaded 60 member of greater pitch is a clutch member which, like the pinion, is projected in the direction of the ring gear when the associated threaded member overruns the clutch member due to inertia of the latter. The clutch 65 member and pinion are, when in retracted

position, normally spaced a slight distance from each other, but, when the overrunning actions specified take place, the pinion starts its projective movement and goes into mesh with the engine gear before the clutch member has been overrun by the threaded member of greater pitch the amount necessary to effect sufficient projection of the clutch member to take up the normal spacing mentioned, overtaking and binding against the pinion. 70 Preferably, though not essentially, the threaded member of lesser pitch is journaled upon the drive shaft and rotates in unison with the threaded member of greater pitch solely by reason of frictional coupling therewith. When the clutch has, by reason of its greater rate of projection, overtaken the still projectively moving pinion, a progressive binding action is initiated and the clutch and pinion continue to move as a unit on their respective threaded members, becoming more and more tightly wedged upon themselves and the threaded members by reason of the differential threading thereof, binding the threaded member of lesser pitch, if of the 75 floating type, upon the drive shaft and the other threaded member, gradually picking up the load and continuing the progressive binding action while more and more load is being picked up. Thus it will be seen that 80 there is no positive stop in the present construction, no "locking" of the pinion to start the cranking action as in the drives heretofore known, but a gradual, progressive binding of the pinion upon several members, 85 which binding is proportional to the load being undertaken. The pinion has no definite limit of projective movement as positively determined by the elements of other devices for performing cranking operations, but to 90 the contrary, travels on its individual worm a distance proportional to the load undertaken.

Referring now, more particularly, to the preferred embodiment of my invention illustrated in Figs. 1 to 5 of the drawings, my starter drive comprises a drive shaft 10 driven by the starting motor 11, upon which shaft are mounted a pair of differentially threaded sleeves or worms 12 and 13. The outer sleeve 12 is keyed, pinned or splined to the drive shaft 10 as by means of a key 14. If desired, the assembly collar 15 secured to the end of the shaft 10 by a pin 16 may be formed integral with the worm sleeve 12 and the key 14 may be omitted. At the other end of the drive shaft 10, adjacent the motor 11, is provided a thrust collar 17 secured thereto by means of a pin 18, and the worm sleeve 13 is journaled between the collar 17 and worm 12. 115 For the purpose of frictionally associating the worm 13 with the shaft 10 and worm 12, thrust collars 13b and 13c are provided thereon. Upon the worm 13 is mounted a pinion gear 19 having teeth 19a for engagement with 120

the teeth 20a of the flywheel ring gear 20 of the engine (not shown). The pinion 19 has threads 19b which are associated with the threads 13a of the worm sleeve 13 and which cause the pinion to travel toward the ring gear 20 when the worm 13 is rotated by the starting motor. At the outer end of the pinion is formed a conical clutch portion 19c within which the complementary conical 5 clutch face 21b of the clutch member 21 is receivable. Clutch member 21 is carried by the worm sleeve 12 and has threads 21a which are associated with the threads 12a of the worm sleeve 12, and which cause the clutch 10 member 21 to be projected toward the ring gear 20 when the worm sleeve 12 is rotated by the motor 11. Worm sleeves 12 and 13 are differentially threaded, that is their threads 12a and 13a turn in the same direction, but the threads 12a have greater lead 15 or pitch than the threads 13a. In normal inoperative position the clutch member 12 is retracted adjacent the collar 15 and the pinion 19 is retracted to the limit defined by the unthreaded end 13d of the worm sleeve 13. In these retracted positions, the clutch face 21b of the clutch member 21 is spaced from the clutch face 19c a distance sufficient to allow the pinion 19 to mesh with the ring gear 20 a substantial distance before the clutch 20 member 21, by reason of its threads 21a of greater pitch and its consequent greater speed of projection, overtakes and binds the pinion 19 to transmit torque. For the purpose of maintaining a fairly accurate timing 25 for this binding action so that proper meshing of the pinion and ring gears is assured, as well as for the purpose of eliminating any tendency of the pinion 19 to accidentally roll down the worm sleeve 13 into engagement with the ring gear 20 when the engine is not level, a collar 22 is pressed on the clutch member 21 and loosely ties the clutch member and pinion 19 against becoming widely 30 separated. Slots 23 are preferably formed in the face 21b of the clutch member 21, which slots permit more accurate conformity of the face 21b to the pinion face 19c and provide smoother action.

35 The operation of the device is extremely simple. When the starting motor 11 is energized, the shaft 10 is revolved, viewing the outer end of the illustrated embodiment, in a counter-clockwise direction. Worm sleeve 12 is, by reason of its keyed relation to the shaft, rotated counter-clockwise, as is worm sleeve 13, by reason of its frictional association with shaft 10, collar 17 and sleeve 12. Pinion gear 19 and clutch member 21, by reason of their inertia, do not instantly start 40 to rotate with their respective worm sleeves 13 and 12, but are fed toward the starting motor end of the shaft 10. Pinion 19, being initially spaced from clutch member 21, is projected upon its worm 13 until it is well 45 meshed with ring gear 20 before it is overtaken by the more rapidly projected clutch member 21. The two elements, clutch member and pinion, having contacted, now begin to bind and tend to rotate with the drive shaft 10. The tendency to bind is a progressive action, very light at the start, due, in part, probably, to the fact that ring gear 20 has arrested the tendency of pinion 19 to start spinning with its worm so that, in effect, there is no reduction in the rate of its projection, whereas clutch member 21, not being so arrested, has taken on some rotative movement and its winding-up on its worm is less rapid than at the start. At any rate, what occurs after the meshing of the pinion and the initial contact of faces 21b and 19c is a progressive and joint winding-up of clutch member and pinion upon their respective worms, effecting a gradual binding of the several parts; worm sleeve 13 with collar 17; pinion threads 19b with worm threads 13a; clutch threads 21a with worm threads 12a; and clutch face 21b with clutch face 19c. Actual observation discloses that pinion 19 and clutch member 21 may turn with respect to drive shaft 10, under heavy load, nearly a complete revolution after initial contact of faces 21b and 19c has taken place. I consider this progressive load take-up feature of my invention to be a revolutionary departure from all other systems for accomplishing the cranking of internal combustion engines.

50 The disengagement of the pinion 19 from the ring gear 20, when the engine starts, is as quiet and easy as is the engagement. At the first tendency of the pinion to overrun the drive shaft 10, the pinion tends to wind rearwardly upon the worm threads 13a. Due to the frictional engagement of clutch face 19c with clutch face 21b, clutch member 21 tends to rotate with pinion 19 and, due to the greater pitch of its threads, once started to overrun shaft 10, contact of faces 21b and 19c is broken and the parts return to their retracted, normally spaced relation defined by collar 15 and worm end 13d. The ease with which disengagement is effected has been demonstrated experimentally by manually setting the parts in driving relation, clamping the pinion in a vise, and tightening the drive shaft with an eighteen-inch pipe wrench until no further binding could be effected by manual pressure upon the wrench. The drive, still thus engaged, was removed from the vise, and by grasping the drive shaft in one hand, and turning the pinion gear with the other hand to simulate starting of the engine, the engagement was broken with but the barest effort.

55 A very important feature of my device is its unique action when, due to excessively advanced ignition, the engine kicks or runs backward instead of starting. Under such 60 conditions, the pinion 19, being initially spaced from clutch member 21, is projected upon its worm 13 until it is well 65

conditions, the pinion 19, instead of remaining locked upon the drive shaft, as in the case of conventional starter drives, causes the floating worm member 13 to slip upon the drive shaft, and the clutch face 19c of the pinion itself slips upon the clutch face 21b of the clutch member 21 without effecting any material separation therefrom or projection of the pinion toward the starting motor. When the engine ceases to violently react against the drive, and the drive is resumed by the starting motor, the clutch member is slightly further projected and the progressive grinding action again takes place, to the resumption of the cranking operation.

It is to be noted that, by reason of the engagement of the conical faces 21b and 19c of the clutch member and pinion, the latter is centered upon the drive shaft 10 so that positive alinement of the pinion 19 with the ring gear 20 is assured. Due to the fact that no torque spring is employed in the drive, the usual periods of deceleration in the cranking action inherent to such spring drives are eliminated. Moreover, due to the fact that the pinion gear is meshed with the engine gear before any torque is applied thereto, burring of gear teeth is precluded. In fact, the entire action of the device is such that the drive may be operated repeatedly while the engine is running, and the interference of the pinion with the engine gear is so slight as to hardly be audible over the sound of the engine. Moreover, careful examination of the pinion and engine ring gears after such abuse, long continued, failed to reveal even the finest scratch on either gear.

In Figs. 6 to 11, I have disclosed a modified form of my invention in which the threaded members or worms are not similar, one being internal and the other external. As in the first illustrated embodiment, however, the essential features of differential threading, and spacing of clutch and pinion to effect timed, progressive binding after meshing of pinion with engine gear, are present. In this modified form, there is a drive shaft 10 driven by the motor 11, a thrust collar 17 secured to the drive shaft adjacent the motor 11 by means of a pin 18, a floating worm sleeve 13 having its forward end 13c abutting the collar 17 and held adjacent thereto by a split ring 33b, a pinion gear 39 threadedly associated with the worm sleeve 13, limited in retractive movement by the end 13d of the worm sleeve, and having a clutch portion 39c. Upon the rear end of the drive shaft is pinned a cup-shaped member 32, internally threaded in the same direction as worm sleeve 13 but having threads of greater pitch. Within the threaded member 32 is disposed the end of a clutch member 41 bearing threads 41a which are engaged with those 32a of the member 32. The member

32 is preferably recessed at 32b to preclude any tendency of the member 41 to stick when retracted to the limit of its movement. Upon the forward end of clutch member 41 is carried a slightly conical friction washer 41b which is normally spaced from the clutch face 39c of the pinion when the parts are in retracted position. For the purpose of preventing the clutch member 41 and pinion from becoming too widely separated, as well as for eliminating any tendency of the pinion to roll upon its worm member when the engine is not level, there are provided lugs 42 on the washer 41b which are received loosely in notches 42a in the pinion clutch portion 39c. Due to the fact that the spacing of the washer 41b and portion 39c is slight, the relative rotation therebetween necessary to effect their contact is slight, and the notches 42a need not be much wider than the lugs 42. In order to permit slippage in the event of kicking or running backward of the engine, the washer 41b is snugly journaled on the clutch body proper and is held in assembly therewith by the split ring 41c.

The operation of the device illustrated in Figs. 6 to 11 is substantially the same as that shown in Figs. 1 to 5. Rotation of shaft 10 by the motor 11 causes pinion 39 to engage engine ring gear 20. Clutch member 41 is at the same time moved toward pinion gear 39, and due to the greater pitch of the threads 32a of member 32, washer 41b overtakes the clutch face of pinion portion 39c shortly after the engagement of pinion 39 with ring gear 20. Progressive binding action of the several parts is then initiated and continues, gradually picking up more and more of the load, as in the case of the device illustrated in Figs. 1 to 5.

I am aware that my invention is capable of numerous embodiments, the two devices illustrated being merely illustrative. Likewise, numerous changes might be made in the illustrated devices. For example, the pinion-associated worm sleeve 13 might take the form of an internally threaded member; also, it might be keyed to the drive shaft 10, although, in practice, I have found it desirable, from the standpoint of ease of engagement and disengagement, as well as accommodation of engine kick, to have this part merely frictionally associated with the drive shaft or other threaded member. For the purpose of increasing its coefficient of friction, a spring may be provided on shaft 10 to initially urge collar 13c more tightly against collar 17. Numerous forms of clutches are available as equivalents of those illustrated, although I prefer conical faces thereon because of the centering effect they have upon the pinion gear. In actual practice, I have found that the space-limiting members 22 or 42 and 42a are not essential, the parts normally tending to assume and remain in

proper spaced relationship and offer no interference with the ring gear 20. The slots 23 in the clutch member forming a part of the device illustrated in Figs. 1 to 5 are likewise not essential to the invention, adequate engagement being attainable without them. I believe the concept of providing a self-governing progressive drive for performing cranking of internal combustion engines and like functions, which progressive drive is effected by the action of a pair of differentially threaded members, is a revolutionary step in this art and, therefore, claim my invention broadly, as indicated by the appended 10 claims.

What I claim is:

1. In an engine starter drive, the combination of a pair of aligned differentially threaded members, the one having threads 20 of greater pitch being rotated by the prime mover, and the one of lesser pitch being rotatable in unison with the threaded member of greater pitch, a drive-transferring pinion carried by the threaded member of lesser 25 pitch and having threads engaged therewith effective, when overrun by the associated threaded member, to project said pinion into drive-transferring engagement with the engine to be driven and effective, when the pinion overruns the associated threaded member, to retract said pinion from said drive-transferring engagement, and a clutch member carried by said threaded member of greater pitch and normally spaced from clutching 30 engagement with said pinion, said clutch member having threads engaged with those of the member by which it is carried and effective, when overrun by its associated member, to overtake, clutch, and travel with 35 said pinion member after the latter has been projected so that by the differentially threaded character of the threaded members the several parts will be progressively bound together for rotation as a unit.
- 45 2. In an engine starter drive, the combination of a pair of aligned differentially threaded members, the one having the threads of greater pitch being rotated by the prime mover and the one of lesser pitch being rotatable in unison with the threaded member 40 of greater pitch, a drive-transferring pinion carried by the threaded member of lesser pitch and having threads engaged therewith effective, when overrun by the associated 45 threaded member, to project said pinion into drive-transferring engagement with the engine to be driven and effective, when the pinion overruns the associated threaded member, to retract said pinion from said drive-transferring 50 engagement, and a clutch member carried by said threaded member of greater pitch, said clutch member having its clutch face of conical form, normally spaced from but engageable with a complementary portion of said pinion whereby centering and

alignment of the latter with respect to the axis of rotation is assured, said clutch member having threads engaged with those of the member by which it is carried and effective, when overrun by its associated member, to overtake and engage its conical face with the complementary portion of said pinion after the latter has been projected so that by the differentially threaded character of the threaded members the several parts will be progressively bound together for rotation as a unit.

3. In an engine starter drive, the combination of a drive shaft, a pair of aligned differentially threaded members thereon, the one having the greater pitch being rotated by the drive shaft, and the other being rotatably journaled upon the drive shaft and frictionally associated therewith so as to normally rotate in unison with the threaded member of greater pitch, a drive-transferring pinion carried by the threaded member of lesser pitch and having threads engaged therewith effective, when overrun by the associated threaded member, to project said pinion into drive-transferring engagement with the engine to be driven and effective, when the pinion overruns the associated threaded member, to retract said pinion from said drive-transferring engagement and a clutch member carried by said threaded member of greater pitch and normally spaced from clutching engagement with said pinion, said clutch member having threads engaged with those of the member by which it is carried and effective, when overrun by its associated member, to overtake, clutch, and travel with said pinion member after the latter has been projected so that by the differentially threaded character of the threaded members the several parts will be progressively bound together for rotation as a unit.

4. In an engine starter drive, the combination of a drive shaft, a pair of aligned differentially pitched screw sleeves thereon, the one having the greater pitch being rotated by the drive shaft, and the one of lesser pitch being rotatable in unison with the screw sleeve of greater pitch, a drive-transferring pinion carried by the screw sleeve of lesser pitch and having threads engaged therewith effective, when overrun by the associated screw sleeve, to project said pinion into drive-transferring engagement with the engine to be driven and effective, when the pinion overruns the associated screw sleeve, to retract said pinion from said drive-transferring engagement, and a clutch member carried by said screw sleeve of greater pitch and normally spaced from clutching engagement with said pinion, said clutch member having threads engaged with the screw sleeve by which it is carried and effective, when overrun by its associated screw sleeve, to overtake, engage, and travel with said pinion

after the latter has been projected, so that by the differentially pitched character of the screw sleeves the several parts will be progressively bound together for rotation as a unit.

5. In an engine starter drive, the combination of a drive shaft, a pair of alined differentially pitched screw sleeves thereon, the one having the greater pitch being rotated by the 10 drive shaft, and the one of lesser pitch being rotatably journaled upon the drive shaft and frictionally associated therewith so as to normally rotate in unison with the screw sleeve of greater pitch, a drive-transferring 15 pinion carried by the screw sleeve of lesser pitch and having threads engaged therewith effective, when overrun by the associated screw sleeve, to project said pinion into drive-transferring engagement with the engine to 20 be driven and effective, when the pinion overruns the associated screw sleeve, to retract said pinion from said drive-transferring engagement, and a clutch member carried by 25 said screw sleeve of greater pitch and normally spaced from clutching engagement with said pinion, said clutch member having threads engaged with the screw sleeve by which it is carried and effective, when overrun by its associated screw sleeve, to overtake, 30 clutch, and travel with said pinion after the latter has been projected, so that by the differentially pitched character of the screw sleeves the several parts will be progressively 35 bound together for rotation as a unit.

35. 6. In an engine starter drive, the combination of a drive shaft, a pair of alined differentially threaded members thereon, the one having the greater pitch being positively driven by the drive shaft, and the one of lesser pitch 40 being rotatively associated to normally rotate in unison with the threaded member of greater pitch, a drive-transferring pinion carried by the threaded member of lesser pitch and having threads engaged therewith effective, when overrun by the associated 45 threaded member, to project said pinion into drive-transferring engagement with the engine to be driven, and effective, when the pinion overruns the associated threaded member, to retract said pinion from drive-transferring engagement, a clutch member carried by said threaded member of greater pitch and having threads engaged with those of the member by which it is carried, and means associated with said pinion for providing a predetermined amount of spacing between said pinion and said clutch member when in retracted 50 positions, so that when overrun by their respective threaded members, the pinion will first be projected into drive-transferring engagement with the engine and said clutch member will, by reason of the greater pitch of its associated threaded member, overtake, clutch, and travel with said pinion member so as to progressively bind the several parts of the device together for rotation as a unit, said spacing means including a stop for limiting the extent of retraction of the clutch member, a stop for limiting the extent of retraction of the pinion member, and means bridging the clutch member and pinion for determining the maximum amount of spacing therebetween.

7. In an engine starter drive, the combination of a drive shaft, a pair of alined differentially threaded members thereon, the one having the greater pitch being positively driven by the drive shaft, and the one of lesser pitch being rotatively associated to normally rotate in unison with the threaded member of greater pitch, a drive-transferring pinion carried by the threaded member of lesser pitch and having threads engaged therewith effective, when overrun by the associated threaded member, to project said pinion into drive-transferring engagement with the engine to be driven, and effective, when the pinion overruns the associated threaded member, to retract said pinion from drive-transferring engagement, a clutch member carried by said threaded member of greater pitch and having threads engaged with those of the member by which it is carried, and means associated with said pinion for providing a predetermined amount of spacing between said pinion and said clutch member when in retracted positions, so that when overrun by their respective threaded members, the pinion will first be projected into drive-transferring engagement with the engine and said clutch member will, by reason of the greater pitch of its associated threaded member, overtake, clutch, and travel with said pinion member so as to progressively bind the several parts of the device together for rotation as a unit.

70. 8. In an engine starter drive, the combination of a prime mover, a pair of differentially threaded members mounted to rotate with said prime mover, a pinion having screw-threaded engagement with one of said members, and a clutch element having screw-threaded engagement with the other of said members, whereby simultaneous rotation of said threaded members will project said pinion to driving position and move the clutch element relative to the pinion into clutching engagement with the latter.

75. 9. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

80. 10. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

85. 11. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

90. 12. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

95. 13. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

100. 14. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

105. 15. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

110. 16. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

115. 17. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

120. 18. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

125. 19. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

130. 20. In an engine starter drive, the combination of a prime mover, a drive shaft rotated thereby, a pair of differentially threaded members mounted on said shaft to rotate therewith, a pinion having screw-threaded engagement with one of said members, and a clutch element having screw threaded engagement with the other of said members, whereby rotation of said shaft will project said pinion to driving position and move the clutch element relative to the pinion into clutching engagement therewith.

10. In an engine starter drive, the combination of a starting motor, a drive shaft rotated thereby, a pair of differentially threaded members on said shaft, one being fixed thereto, a pinion having screw-threaded engagement with one of said members, and a clutch element having screw-threaded engagement with the other of said members and movable by differential screw action into and out of 10 clutching engagement with the pinion.

11. In an engine starter drive, the combination of a starting motor, a drive shaft rotated thereby, a screw sleeve fixed thereto, a second screw sleeve of lesser pitch frictionally 15 mounted on said shaft, a cone clutch member screwed on the sleeve of greater pitch, and a pinion screwed on the sleeve of lesser pitch and having a cone clutch portion complementary to that of said member.

20 PHILIP S. CLAUS.
